BODY COOLER

Henry C. Everett, 1106 S. Euclid St., Champaign, Ill.
Filed Oct. 31, 1960, Ser. No. 66,188
1 Claim. (Cl. 62—259)

This invention relates to new and useful improvements in a device for cooling the human body. Generally, it comprises a pair of insulated containers constructed of non-porous material, adjustable means for positioning these containers under each arm of a human body, and holding them in place, and a coolant which is positioned within the containers.

It has been well known prior to this invention that it is possible to reduce the temperature of the entire human body by localized applications of a suitable coolant. However, none of the previously known devices provided a suitable means for applying such coolants under the arms, where a concentration of blood vessels near the outer surface of the skin make this an ideal spot on the body to apply the coolant to achieve the most effective results.

It is therefore an object of this invention to provide a means for properly positioning and holding in place under the arms an effective coolant with a resultant decrease in mean body temperature.

It is a further object to provide such a means which can be fully utilized while the user is nevertheless fully clothed, and without creating unsightly and embarrassing bulges in the clothing.

It is still a further object to provide such a means for lowering the body temperature which will not absorb body moisture, and will thus avoid becoming damp and easily soiled.

It is yet another object to provide a means for holding a coolant in place under the arms which is adjustable to adapt to any width shoulders, and also elastic to allow freedom of movement after it has been adjusted to the proper snug fit.

Further objects and advantages will become apparent upon examination and consideration of the accompanying drawings in which:

FIGURE 1 is a general view showing the body cooler in place on a human body,

FIGURE 2 is a view of one of the coolant containers,

FIGURE 3 is a view showing a cross-section through the container, the section being taken through the shortest vertical dimension of the container,

FIGURE 4 is a view showing a cross-section through the container, the section being taken through the longest vertical dimension of the container, and

FIGURE 5 is a perspective view of a coolant pellet to be used with the body cooler.

Referring now more particularly to the drawings, it will be seen in FIGURE 1 that the body cooler comprises

2

containers 11, one of which has a strap 12 affixed to its upper extremities, which strap 12 in turn has a strap 13 stitched to it, or permanently attached by other means. The remaining container 11 likewise has a strap 12 attached to its upper extremities, but this strap 12 is not permanently fixed to strap 13. Strap 13 extends from its end fixed to strap 12, encircles the other strap 12, and terminates in a well-known sliding fastener 14. The coolant pellet 15 shown in FIGURE 5 is preferably of a sublimating material such as carbon dioxide. It is placed in the containers 11, and the straps 12 placed over the shoulders of the body 10 as shown in FIGURE 1. In FIGURES 2 and 4 are shown the metal snap fasteners 20 which are engaged to hold the pellet within the containers. In FIGURES 3 and 4 is shown the construction of the container walls, the inner wall 16 being a non-porous material such as plastic, the insulating layer 17 being a material in the nature of fiberglass, and the outer wall 18 being plastic.

In operation, the coolant pellet is placed in the containers, and the top snapped shut by the fasteners 20. The arms are then placed through the loops formed by the straps 12 so that the strap 13 is positioned across the shoulders. The slide fastener 14 is then actuated to cause the strap 13 to fit snugly and lie flat against the shoulders. Thus is provided a device which applies a coolant in an effective position under each arm. The skin is cooled by the coolant pellet, but is also protected from "burns" which might be caused by direct contact with the skin.

Having shown and described one embodiment of the invention, it is to be understood that various changes and modifications may be made without departing from the spirit of the invention or the scope of the appended claim.

I claim:

A device for cooling the human body comprising containers having an upper, open end, continuous straps attached to the extremities of the upper, open end of said containers to form loops, a strap fixedly attached to one of said loops and extending horizontally therefrom and encircling another of said loops, and terminating in an adjustable slide fastener, said containers having a plastic inner wall, a plastic outer wall, and an insulating fiberglass layer between said inner and outer walls, and snap fasteners operable to close said upper open end of said containers, a coolant pellet, said containers adapted to receive said coolant pellet.
